UNITED STATES PATENT OFFICE.

GEORGE A. BADGER AND WILBER F. LAKIN, OF QUINCY, MASSACHUSETTS.

TOY PISTOL.

SPECIFICATION forming part of Letters Patent No. 335,104, dated February 2, 1886.

Application filed May 4, 1885. Serial No. 164,322. (Model.)

To all whom it may concern:

Be it known that we, GEORGE A. BADGER and WILBER F. LAKIN, both of Quincy, in the county of Norfolk and State of Massachusetts, have invented a new and useful Improvement 5 in Toy Pistols, of which the following is a specification.

The invention relates to the construction and mechanism of toy pistols and the object 10 or missile to be expelled therefrom.

The object of our invention is to provide a toy pistol for children, for parlor and other practice, that is safe, accurate for short distances, and durable.

15 The invention consists in improvements in the arrangement and mechanism of the different parts of a toy pistol.

Our invention further consists in a rod, made of wire or other suitable material, attached to 20 the butt or handle of a toy pistol, and adapted to pass through the center of a ball, and operating as a guide to the ball when expelled.

Our invention further consists in a coiled-wire spring attached at one end to the butt or 25 handle of a toy pistol, and the other end attached to a sliding sleeve, having a rod or guide passing through the center of said spring and sleeve, and adapted to be contracted, retained, and again released, to cause the expulsion 30 of a ball moving on said guide or rod.

Our invention further consists in a catch, trigger, or retaining device, adapted to catch, retain, and again release the sliding sleeve and ball, said catch or trigger being actuated by a 35 proper spring.

In the accompanying drawings similar letters of reference indicate like parts.

Figure 1 represents a side elevation of a toy pistol embodying our invention. Fig. 2 represents a vertical longitudinal section of the same.

In the drawings, A represents the butt or handle.

B is the rod or guide, suitably attached to 45 the butt or handle A.

c represents the sliding sleeve, which is permanently attached to the coiled spring g, said spring g being fixedly attached to the butt or handle A.

50 E represents the trigger or catching and releasing device, which is pivoted at or near its

center to the butt A, and constructed with a notch or catch, G, and concaved portion O, adapted to catch, retain, and again release the ball a and sleeve c.

55

H represents the small spring, which is seated at one end upon the butt A, and at the other end upon the trigger E, to cause said trigger and catch to assume its normal position after the sliding sleeve c and ball a, actuated by the coiled spring g, have been released.

60 The operation of our invention is as follows: The ball a, having a hole through its center, is placed upon the rod or guide B and pressed firmly against the sliding sleeve c, which causes 65 the coiled spring g to be compressed until the sleeve c engages with the catch G and the ball a to engage with the concave portion O, by which they are retained, as shown in Fig. 2. Pressing the finger upon the trigger E below 70 the spring H causes the trigger E to move upon its pivot, thereby compressing the small spring H, and causing that portion of the trigger having the catch G and the concave portion O to move below its plane, thereby releasing the sleeve c and ball a, when the coiled spring g, with the sleeve c, is free to act upon the ball a, moving upon the rod or guide B, 75 from which it is expelled.

Having thus described our invention, we 80 claim—

1. In a toy pistol, the combination of a butt or handle, a rod or barrel suitably attached thereto, a compressible coiled spring having one end attached to the butt or handle and 85 the other end attached to a sliding sleeve, and adapted to be compressed and expanded upon the barrel or rod, the sliding sleeve, a trigger or catch pivoted at or near its center upon the butt or handle, and adapted to engage, retain, and release the sliding sleeve and ball or missile to be expelled, and a small spring seated at one end upon the butt or handle and the other end seated upon the trigger, so as to cause it to assume its normal position when released, 90 all arranged and constructed as and for the purpose specified.

2. In a toy pistol, the combination of the handle A, the rod or barrel B, suitably attached to said handle, the compressible coiled 95 spring g, attached at one end to the handle and at the other end to the sliding sleeve c,

the hollow ball *a*, moving upon the rod *B*, the trigger *E*, having the concave portion *O*, adapted to hold the ball, and the small spring *H*, seated upon said handle *A* and trigger *E*, all 5 arranged substantially as and for the purpose specified.

In testimony whereof we have signed our

names to this specification in the presence of two subscribing witnesses.

GEORGE A. BADGER.
WILBER F. LAKIN.
